MULTIPLE BURNER GRILL STAND

Fred Press, New York, N. Y., assignor to Rubel & Company Decorative Accessories, Inc., New York, N. Y.

Application August 1, 1951, Serial No. 16,098

Term of patent 3½ years

(Cl. D81—10)

To all whom it may concern:

Be it known, that I, Fred Press, a citizen of the United States, residing at the city of New York, Borough of Manhattan, county of New York, and State of New York, have invented a new, original, and ornamental Design for a Multiple Burner Grill Stand, of which the following is a specification, reference being had to the accompanying drawing, forming a part thereof.

In the drawing:

Fig. 1 is a perspective view of a multiple burner grill stand showing my new design with the several rotatable members in open position; and

Fig. 2 is a side elevational view thereof with the several rotatable members in closed position.

I claim:

The ornamental design for a multiple burner grill stand, substantially as shown.

FRED PRESS.
